UNITED STATES PATENT OFFICE.

JACOB FISHMAN, OF ST. LOUIS, MISSOURI.

ATTACHMENT FOR CASKETS.

Application filed December 23, 1921. Serial No. 524,467.

To all whom it may concern:

Be it known that I, JACOB FISHMAN, a citizen of the United States of America, and resident of the city of St. Louis, State 5 of Missouri, have invented a new and useful Attachment for Caskets, of which the following is a specification.

This invention has for its prime object the provision of a simple, inexpensive and durable device which can readily be applied to burial caskets for the purpose of enabling relatives and friends of deceased persons to view their features after interment.

In the accompanying drawing, where like numerals refer to like parts throughout, Figure 1 is a partly sectional elevation depicting a casket with the invention applied thereto and in use. Figure 2 a sectional view, on enlarged scale, depicting the position of the inner extensible tube, herein-after described, while the invention is unused, and the manner of closing the upper extremity of said tube; Figure 3 a top view of the mouth of said tube showing the knobs by which it may be raised or lowered; and Figure 4 a fragmentary detail view depicting the door provided in said tube and the electrical battery which is secured to the inner surface thereof.

1 denotes the ground line of a grave, 2 the casket and 3 the box within which the casket is commonly placed. The lid of the casket is provided with a substantially square opening covered with glass and surrounded by an inwardly inclined metal frame 4 to which is secured the base 5^a of tube 5, said opening being so positioned as to disclose the face of the deceased. Hinged-ly secured at the upper extremity of said tube is a cover 6 which may be secured by a padlock 7 when its hasp 8 is brought into engagement with staple 9, and slidably fitting within said tube is an extensible section 10 provided with knobs or handles 11 and a hinged door 12 carrying upon its inner surface a small "flashlight" battery 13 retained by a suitable spring-clip 14.

When it is desired to view the face of the deceased after burial, cover 6 is released, 50 section 10 raised by aid of knobs 11 to the position shown in Figure 1 and the interior of the casket (opposite the lid opening) illuminated by the light supplied by lamp 15 which is secured to or suitably connected 55 with said battery.

On leaving the grave, the person using the attachment may remove the battery to prevent its deterioration and then lower section 10 to the position shown in Figure 2, the cover 6 being finally locked to prevent 60 the admission of rain and particles of earth and to insure that unauthorized persons may not indulge their curiosity.

I am aware that at least one other device comprising a tube extending from the interior of a casket to a point considerably above the surface of the grave has been patented, but the same depends for its utility upon mirrors and lamps mounted within the casket which obviously cannot be replaced when damaged and, moreover, I place special importance upon my use of an extensible tube adjustable to the height of a child or adult and which eliminates any unsightly aspect in a cemetery.

What I claim as new and desire to secure by Letters-Patent is:—

1. An attachment for burial caskets comprising a tube secured at one extremity to the lid of the casket and of length sufficient to extend substantially to the surface of a grave, and a tubular extensible section disposed within and frictionally engaging the walls of said tube adapted to be raised above said surface.

2. An attachment for burial caskets comprising a tube secured at one extremity to the lid of the casket and of length sufficient to extend substantially to the surface of a grave, a tubular extensible section disposed within and frictionally engaging the walls of said tube adapted to be raised above said surface, and means for closing the upper extremity of said tube and preventing withdrawal therefrom of said section.

3. An attachment for burial caskets comprising a tube secured at one extremity to the lid of the casket and of length sufficient to extend substantially to the surface of a grave, a tubular extensible section disposed within and frictionally engaging the walls of said tube adapted to be raised above said surface, an electrical battery secured within said section, and means for inserting and removing said battery.

JACOB FISHMAN.
